UNITED STATES PATENT OFFICE.

EBERHARD SCHNEIDER, OF NEW YORK, N. Y., ASSIGNOR OF ONE-HALF TO
LOWELL MASON, OF SAME PLACE.

DESIGN FOR A PUZZLE BOX OR CASE.

SPECIFICATION forming part of Design No. 30,825, dated May 16, 1899.

Application filed April 11, 1899. Serial No. 712,668. Term of patent 3½ years.

To all whom it may concern:

Be it known that I, EBERHARD SCHNEIDER, a citizen of Germany, residing at New York, in the county of New York and State of New York, have invented and produced a new and original Design for Puzzle Boxes or Cases, of which the following is a specification, reference being had to the accompanying drawings, forming part thereof, in which—

- o Figure 1 is a plan view of a puzzle box or case, showing my new design; and Fig. 2, a sectional view on the line 2 2 thereof.
As shown in the drawings, the leading or material feature of my design consists of a rectangular box or case *a*, which incloses a part *b*, the central portion of which is conical in form on both its upper and lower sides, and the apex of the conical portion *b* is provided with a central vertical opening *c*, and around the said conical portion and extending from the base to the top thereof is a spiral groove *d*, which communicates at the top with the central vertical opening *c*. The spiral groove *d* is enlarged at the base of the cone or at the

point where said groove begins, as shown at ²⁵ *e*, and at the apex of said conical portion, adjacent to the central vertical opening *c*, is a flagstaff and flag *f*. The walls of the spiral groove *d* are also provided at intervals with breaks or openings *g*, by which the separate ³⁰ coils of said groove are placed in communication, and the base of the part *b* within the box or casing *h* and around the base of the conical part thereof is preferably flat and smooth.

Having fully described my invention, I claim as new and desire to secure by Letters Patent—

The design for a puzzle box or case herein shown and described.

In testimony that I claim the foregoing as my invention I have signed my name, in presence of the subscribing witnesses, this 10th day of April, 1899.

EBERHARD SCHNEIDER.
